PILE FABRIC

Leonard L. Crabtree, Bridgeport, Conn., assignor,
by mesne assignments, to The Saltex Looms,
Inc.

Application August 10, 1926, Serial No. 128,434

1 Claim. (Cl. 28—1)

This invention relates to pile fabrics and particularly to upholstery pluses used as coverings for the seats and interiors of automobiles and other vehicles.

- 5 5. One object of the invention is to provide a pile fabric having a cementitious or viscous coating applied to its back to fix the pile threads to the ground or body of the cloth to prevent them from pulling out.
- 10 10. Another object of the invention is to provide a pile fabric of the type specified in which the flock or pile on the face of the goods is stiffened and supported in more erect position due to the coating on its back.
- 15 15. Further objects and advantages of the invention will appear from the detailed description of the improved fabric and a preferred method of manufacturing the same as set forth in the following specification which is illustrated by the accompanying drawing. In the drawing:

Fig. 1 is a view showing a relatively small strip of the coated fabric and illustrating its general appearance both on the face and back;

Fig. 2 is a magnified cross-sectional view showing the structure of the weave of one type of fabric embodying the present improvement and the manner in which the coating is applied thereto; and

Fig. 3 shows a preferred method of weaving the fabric to which the coating is applied.

Pile fabrics such as upholstery plush are usually woven with a mohair or worsted pile, or a combination of the two, and heretofore it has been considered necessary to produce them with a "fast pile" weave in which the pile threads are interlaced with and bound under a plurality of the weft threads in the body of the cloth. In a generally used type of weave the pile threads are interlaced with four weft threads and this takes up a considerable amount of the pile yarn which is the most costly element of the cloth. That is to say, a large percentage of the pile material is taken up by the "knees" which loop repeatedly over and under the weft threads, these knees serving to bind the pile firmly into the ground or back of the fabric, but on the other hand not adding in any way to the "cover" to render the pile more dense.

In all fast pile fabrics where the knees of the pile pass above the weft threads they show through on the face of the cloth and have a lighter appearance in color than the effective shade or color of the piece. That is to say, in looking at a pile fabric one looks into shadow so that the standing pile threads appear darker

than the lengths which constitute the knees or overlying loops of thread passing across the lateral weft threads. This showing of the knees with a lighter appearance gives what is called a "grinning through" of the back of the cloth and is present even though the warp and weft threads are dyed black; the knees of the pile threads being the same shade as the pile itself, but, as before explained, showing much lighter in flat position than the upright pile and thus making 10 a contrast with the effective color of the pile. This defect in the appearance of pile fabrics has long been appreciated but has never been overcome because, as before stated, it is necessary in a fast pile fabric to have the knees of 15 the pile threads extending in loops overlying the weft threads in the ground or body of the cloth.

In a "loose pile" fabric the pile is bound into the ground by single picks of weft, each pile 20 thread being looped under one weft thread without overlying adjacent picks of the weft. For this reason the pile threads do not show in loops lying across the top of the ground fabric and hence there is no grinning through. The pile therefore 25 has a better appearance, but, on the other hand, loose pile fabrics are not suitable for upholstery goods since the pile is not securely and permanently bound into the ground or back of the cloth. Moreover, in a loose pile fabric the pile 30 ends do not stand as erect so that the surface of the cloth does not present as good an appearance, and neither has it the same capacity to resist wear as in a fast pile.

The present invention is more particularly directed to improvements in so-called loose pile fabrics and contemplates the anchoring or binding of the pile into the ground or back of the cloth by means of a cementitious or viscous coating, for example, a cellulose compound such as 35 pyroxylin.

Referring to the drawing, Fig. 2 shows a longitudinal sectional view or profile of one type of loose pile fabric constituted by longitudinal ground warp threads 2, lateral weft threads 3 45 interwoven therewith, and pile threads 4 looped around the weft threads 3 and standing erect or in perpendicular relation with respect to the body or ground of the fabric. Each pile thread 4 is bound under a single weft thread 3 by means of 50 its loop or knee 5, and the ends of the pile threads are brushed or frayed out to mingle in the standing tufts as shown. This type of loose pile fabric may be produced with any suitable weave, a preferred method being to weave the fabric double 55

in the manner as conventionally illustrated in Fig. 3. In this view two sets of warp yarns 2 extend in parallel relation one above the other, with the weft threads 3 interwoven respectively therewith; while the pile warp yarns 4 are interlaced over and under the weft picks of the two different fabrics, and crossing therebetween form the pile floats 6. The two opposite fabrics are thus woven face to face and are cut apart in the loom 10 by a reciprocatory knife which severs the crossing pile floats 6 at points intermediate the two pieces of cloth, whereby the pile-ends are left standing on the face of each piece. It is to be understood, however, that other methods of weaving the pile fabric may be employed with equally good results, the present showing being by way of example only.

The coating compound may consist of a solution of pyroxylin and vegetable oil, or in other 20 cases may be a rubber composition or any other viscous fluid of a cementitious nature capable of adhering to the back of the fabric and hardening thereon.

As usually applied, the cellulose or pyroxylin 25 compounds are spread on to the back of the fabric with a "doctor blade", the cloth being sometimes passed over a rubber roller and under the blade which presses the cloth thereagainst. In applying a rubber compound the usual procedure is to 30 pass the fabric between a pair of calendar rolls which squeeze on a thin layer of the coating.

Fig. 2 of the drawing illustrates the invention as applied to the so-called loose pile weave, 35 in which the pile threads 4 are looped under single picks of weft 3, and the knees 5 formed by the pile loops appear on the back of the goods and do not show on the face or finished surface of the cloth. When the coating is applied to the back of a fabric of this type it will impregnate 40 and penetrate between the interlaced threads to a certain degree; not, however, passing through the weave to such an extent as to show on the face of the goods. The cementitious coating is hardened or set by subjecting it to the drying 45 action of heat and thereafter it acts as a binding agent to amalgamate and unite the threads in the body or ground of the fabric. The knees or loops 5 of the pile threads 4 are thus cemented to the other threads forming the structure of the 50 ground fabric and the pile is therefore made fast to prevent the individual ends from being pulled out. It has also been discovered that when the coating is applied to the back of the fabric in the manner as previously explained it has a tendency 55 to hold the individual threads from creeping or moving out of place and also acts to brace and stiffen the pile so that the ends stand more erect. This results in giving the pile a denser and more lofty appearance, thereby enhancing 60 the general effectiveness of the goods. With the present improvement, therefore, an ordinary loose pile fabric, which, as before explained, may be manufactured at much less cost than a fast pile fabric, is rendered fully as durable and wear-resisting as a fast pile fabric.

As will be seen by reference to the drawing, 65 the fabric includes only the regular ground warp and weft threads together with the pile warp threads. In other words, the fabric is devoid of the extra threads which have hitherto been employed for the purpose of securing the loose pile V's against pulling out of the ground or assuming a non-erect position therein under the influence of frictional wear. This prior practice is exemplified by the United States patent to Reix-

ach, No. 442,749, dated December 16th, 1890, where the use of such extra threads in the form of additional warp threads, and the purpose thereof, is clearly shown and described. As set forth in the said prior patent, there are employed as many of the extra or additional warp threads as there are pile threads, so that this manner of proceeding in the effort to fix the loose pile V's firmly in the ground has entailed greatly increasing the number of warp threads 10 for any given quantity of fabric with its necessarily great increase in material and labor. Another exemplification of the prior practice is the United States patent to Pearson, No. 484,605, dated October 18th, 1892, in which patent there is employed an extra set of weft threads which lie directly behind the pile loops, as well as extra pairs of warp threads which serve to hold the extra wefts in position. In this prior arrangement the number of weft threads is increased by an amount equal to the number of weft threads over which pile threads are looped, and the number of warp threads is doubled, so that this amplification of Reixach's procedure still further, and to a very large amount, increases the required material and labor. It is believed that these concrete illustrations from the prior art are sufficient for the purpose in hand, but it may be added that the above named Pearson patent 20 takes note of the desirability of the V-pile weave, as compared with the well known W-pile weave, 25 from the point of view of economy of pile threads and appearance, and that it also explains the unsuitability of the V-pile weave, from the point of view of wear, because of the backing out or pulling out of the pile V's. My invention obviates all this extra material and labor and substitutes therefor the simple procedure herein indicated which involves merely the application of a thin coating of cementitious binding material 30 to the back of ordinary loose V-pile fabric woven, as illustrated, without the extra or additional threads. This, as is well known and will be understood by all those skilled in the art, is a very simple and cheap operation both in labor 35 and material. The result of my invention is a fabric of the kind indicated which is produced at a great saving as compared with the prior practice of using extra threads, and in which the loose pile V's are better secured against movement while the fabric itself is of better appearance.

When, in the claim or claims, I refer to the ends of the pile V's, I intend to designate those parts of the V's adjacent the proximate weft 55 threads, as it is customary to designate the sides of the pile V's as those parts adjacent the proximate ground warps.

Further advantages of the present invention 60 will suggest themselves to vehicle body-builders and others skilled in the upholstery arts, and it is to be understood that the present improved fabric may be applied to other uses than those herein specified. It is also to be understood that various modifications may be made in the character of the weave of the fabric, in the composition of the material used as a coating, and in the method of applying the coating, without departing from the spirit and scope of the invention. Therefore, without limiting myself in 65 those respects, I claim:

A textile pile fabric intended for frictional wear comprising, a ground of interwoven warp and weft threads, rows of substantially uniform and substantially uniformly spaced interwoven

- loose warp pile V's each looped about a single
weft thread but not interlaced with the ground
so as to be thereby firmly held therein, said weft
threads being spaced no further apart than
5 the diameter of the pile threads and alternate
weft threads being in contact with the ends of
intermediate pile V's, said fabric being devoid
of extra or additional threads which would nor-
mally be necessary to secure the V's therein and
10 to render the fabric suitable for frictional wear,
whereby, due to the absence of said extra threads,
the V's would be liable to assume a less erect and
less uniform position and to pull or push out of

the ground when subjected to frictional wear, said
fabric embodying a thin application of cementitious
binding material on the back of the ground
which penetrates the interwoven threads but does
not conceal the weave and unites the loops of
the V's with the interwoven ground warp and weft
threads to anchor the V's against pulling or pushing
out of the ground or assuming a less erect
or less uniform position, whereby the fabric is
rendered suitable for frictional wear and its uni-
formity and appearance are improved without
sacrificing its folding and rolling characteristics.

CERTIFICATE OF CORRECTION.

Patent No. 2,007,078.

July 2, 1935.

LEONARD L. CRABTREE.

It is hereby certified that error appears in the printed specification of the above numbered patent requiring correction as follows: Page 3, second column, lines 4 and 5, the claim, strike out the words "but does not conceal the weave"; and that the said Letters Patent should be read with this correction therein that the same may conform to the record of the case in the Patent Office.

Signed and sealed this 20th day of August, A. D. 1935.

Leslie Frazer
